UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

WINDOW-SCREEN.

1,078,827.

Specification of Letters Patent. Patented Nov. 18, 1913.

Application filed January 25, 1912. Serial No. 673,387.

To all whom it may concern:

Be it known that I, MORTON G. BUNNELL, a citizen of the United States of America, and resident of Chicago, Cook county, Illinois, have invented a certain new and useful Improvement in Window-Screens, of which the following is a specification.

My invention relates to automatic window screens of that kind in which the wire cloth or gauze is carried on a roll in the window frame, the edge of the said cloth or gauze being secured to the sash of the window, and the screen being automatically brought into use each time the window is opened by 10 raising or lowering the sash, it being understood that a screen of this kind can be used at either the top or the bottom of the window.

The object of my invention is to provide novel and effective means for removably securing the edge of the screen to the window sash, whereby the window can be opened without operating the screen, as will hereinafter more fully appear.

To this and other useful ends, my invention consists in matters hereinafter set forth and claimed.

In the accompanying drawings—Figure 1 is a front elevation of a window with the lower sash thereof partially open. Fig. 2 is an enlarged cross section through the lower portion of the sash on line 2—2 in Fig. 1. Fig. 3 is a front elevation of a portion of the mechanism. Fig. 4 is a perspective of a fragment of the lower portion 35 of the sash.

As thus illustrated, my invention comprises a screen A attached to the lower sash B of a window of any suitable form or character. The lower edge of this screen, which 40 is made of wire cloth, is secured to a roller (not shown) in the box a which sets in the window frame below the sash. The side edges of the screen travel up and down in the guides a' at the sides of the window frame. As the said roll and guides are not a part of the present improvement, no further explanation thereof is necessary.

The screen A has its upper edge provided with a metal binding a² in the form of a 50 strip of sheet metal folded to receive and hold the upper edge portion of the screen. This metal binding strip a² is provided at intervals with openings a³ which engage the heads of screws a⁴ inserted in the sash.

These screw heads serve also to hold a strip 55 of felt a⁵, or similar material, upon the face of the sash. A metal strip a⁶ is held in place on the sash by screws a⁷, whereby the strip a⁵ is further clamped and held in place. The metal binding strip a² bears against 60 the cloth strip a⁵ below the clamping strip a⁶ to make a tight joint. The locking levers a⁸ are pivoted on the strip a⁶ by rivets a⁹, and are provided with portions a¹⁰ which move over the binding strip a² to hold the 65 latter in place on the sash. These levers have their upper ends connected by a rod a¹¹, and the middle lever has a handle a¹², whereby the operation of one lever serves to operate them all in unison. When the levers 70 are disengaged from the strip a², the screen can then be disengaged from the sash, and the latter can then be opened and closed without operating the automatic screen. The sash is provided with the usual handles 75 a¹³ by which it is raised and lowered.

From the foregoing it will be seen that by my invention I provide an automatic window screen that can be readily connected with and disconnected from the sash. The 80 mechanism by which the screen is locked to the sash is controlled by the single handle a¹² in the manner shown and described. In this way the screen can be quickly brought into use, and when not needed is easily disconnected to leave the sash free to open and close independently. Also, this makes it 85 possible to readily disconnect the screen in cleaning the window.

What I claim as my invention is: 90

1. In combination with a window sash, a screen, means for connecting the screen with the sash, mechanism on the sash for removably locking the screen in place, said means comprising a strip of compressible material 95 on the sash, a series of projections along said strip, and a strip on the screen for engaging said compressible strip, provided with openings for said projections.

2. In combination with a window sash, a 100 screen, means for connecting the screen with the sash, mechanism on the sash for removably locking the screen in place, said means comprising a strip of compressible material on the sash, a series of projections along said 105 strip, and a strip on the screen for engaging said compressible strip, provided with openings for said projections, said mechanism

comprising devices on the sash for compressing the two strips together to make a tight joint and keep the projections in the openings.

5 3. In combination with a window sash, a screen, means for connecting the screen with the sash, and mechanism on the sash for removably locking the screen in place on said means, non-yieldingly held in locking engagement therewith, including a metal strip by which said mechanism is removably mounted on the sash.

15 4. In combination with a window sash, a screen, means for connecting the screen with the sash, mechanism on the sash for removably locking the screen in place, including a metal strip by which said mechanism is removably mounted on the sash, and means for making a tight joint held in place by said strip.

25 5. In combination with a window sash, a screen, means for connecting the screen with the sash, mechanism on the sash for removably locking the screen in place, said means comprising studs on the sash, and a strip on the screen provided with openings for said studs, the said mechanism comprising levers pivoted on the sash and adapted to move over the said strip.

35 6. In combination with a window sash, a screen, means for connecting the screen with the sash, mechanism on the sash for removably locking the screen in place, said means comprising studs on the sash, and a strip on the screen provided with openings for said studs, the said mechanism comprising levers pivoted to move over the said strip, and a metal strip whereby said levers are removably supported by the sash.

40 7. In combination with a window sash, a screen, means for connecting the screen with the sash, mechanism on the sash for removably locking the screen in place, said means comprising studs on the sash, and a strip on the screen provided with openings for said studs, the said mechanism comprising levers pivoted on the sash and adapted to move over the said strip, a connection between said levers, and means for operating said levers.

50 8. In combination with a window sash, a screen, means for connecting the screen with the sash, mechanism on the sash for removably locking the screen in place, said means comprising studs on the sash, and a strip on the screen provided with openings for said studs, the said mechanism comprising levers pivoted to move over the said strip, a metal strip whereby said levers are removably supported by the sash, a connection between said levers, and means for operating said levers.

55 9. In combination with a window sash, a screen, means for connecting the screen with the sash, mechanism on the sash for remov-

ably locking the screen in place, said means comprising studs on the sash, and a strip on the screen provided with openings for said studs, the said mechanism comprising levers pivoted on the sash and adapted to move over the said strip, and an endwise movable rod by which all of said levers are connected together.

10 10. In combination with a window sash, a screen, means for connecting the screen with the sash, mechanism on the sash for removably locking the screen in place, said means comprising studs on the sash, and a strip on the screen provided with openings for said studs, the said mechanism comprising levers pivoted to move over the said strip, a metal strip whereby said levers are removably supported by the sash, and an endwise movable rod by which all of said levers are connected together.

15 11. In combination with a window sash, a rolling screen therefor, a strip on the edge of the screen, and means for removably clamping the said strip and sash flatwise together, along the length of said strip, to make a tight joint, and a strip for mounting said means on the sash disposed along the outer edge of the strip on the screen.

20 12. In combination with a window sash, a rolling screen therefor, a strip on the edge of the screen, and means for clamping the said strip and sash flatwise together, along the length of said strip, to make a tight joint, and means engaging said strip for preventing edgewise displacement of said strip in any direction.

25 13. In combination with a window sash, a rolling screen therefor, a strip on the edge of the screen, and means for removably clamping the said strip and sash flatwise together, along the length of said strip, to make a tight joint, said strip having openings therein, the sash having devices for engaging said openings to prevent displacement of the strip and screen in the plane thereof, and a strip for mounting said means on the sash.

30 14. In combination with a window sash, a rolling screen therefor, a strip on the edge of the screen, and means for clamping the said strip and sash flatwise together, along the length of said strip, to make a tight joint, said sash having yielding means engaging said strip to form said joint.

35 15. A window sash and a rolling screen, means for removably connecting the screen with the sash, requiring movement of the edge portion of the screen toward and away from the plane of the sash to connect and disconnect the same, serving to prevent side-wise displacement of the screen on the sash, and mechanism for locking the screen and sash together, said means being disposed between said mechanism and the screen.

40 16. A window sash and a rolling screen,

means for removably connecting the screen with the sash, requiring movement of the edge portion of the screen toward and away from the plane of the sash to connect and disconnect the same, serving to prevent side-wise displacement of the screen on the sash, and mechanism for locking the screen and sash together, said means being disposed between said mechanism and the screen, and

said mechanism having rotation only in a 10 plane parallel with said plane of the sash.

Signed by me at Chicago, Illinois, this 18th day of January 1912.

MORTON G. BUNNELI.
